L. FOOTE

CONNECTER FOR TELEPHONE RECEIVERS AND THE LIKE

Filed Nov. 28, 1925

Fig. 2.

UNITED STATES PATENT OFFICE.

LEONARD FOOTE, OF PEDRO MIGUEL, CANAL ZONE.

CONNECTER FOR TELEPHONE RECEIVERS AND THE LIKE.

Application filed November 28, 1925. Serial No. 71,988.

This invention relates to connectors for telephone receivers and the like, and has for its object the provision of a flexible device for readily holding the metal tips of phones in contact so that the telephone receivers are connected in series, the tips being easily detached when desired.

A further object of the invention is the provision of a connector for phone tips, the connectors being in the shape of sockets molded in strips of flexible material so that any number of units of sockets may be cut from the strip, as desired.

A still further object of the invention is the provision of a phone connector formed of flexible material and in which sockets are provided to receive pairs of tips, with each socket having a flared mouth to facilitate insertion and shoulders to prevent displacement of said tips.

A still further object of the invention is the provision of a connector for holding phone tips in contact with each other made of soft flexible material so that the same, when resting on furniture, will not mar the surface, and in which the pairs of tips are held in contact with each other but out of engagement with any other tips or metal, so that the phones will not be short-circuited at any time.

This invention will be best understood from a consideration of the following detailed description, in view of the accompanying drawing forming a part of the specification; nevertheless it is to be understood that the invention is not confined to the disclosure, being susceptible of such changes and modifications which shall define no material departure from the salient features of the invention as expressed in the appended claims.

In the drawings:

Figure 1 is a view in perspective of the radio receiving set showing my invention applied thereto,

Figure 2 is a horizontal section of the phone tip connector showing a pair of tips held in contact in a cell or socket of the connector,

Figure 3 is a view in perspective of a unit of the phone connector showing a pair of cells or sockets,

Figure 4 is a vertical section of a modified form of the connector,

Figure 5 is a view in perspective of a modified form of connector fitting over a plug.

Referring more particularly to the drawings 10 designates a receiving set having a jack 11 to receive a phone plug 12. The plug 12 has sockets to receive the tips 13 and 14, respectively, of the pairs of phones 15 and 16, a third set of phones 17 being connected in series with phones 15 and 16 by my improved connector 18 which holds the phone tips 19 and 20 and phone tips 21 and 21^a in rigid contact with each other.

As shown more particularly in Figures 2 and 3, the connectors are molded from flexible material to provide sockets 22 into which are adapted to be inserted the phone tips, the material from which the sockets are made being resilient. The walls 23 of the sockets may therefore be distorted when it is intended to insert the tips. As shown in Figure 3, the socket 18^a is shown collapsed by finger pressure. The diameter of each of the sockets is made slightly less than twice the diameter of a tip and is also of such minimum diameter that the inner circumference of the socket is slightly greater than the circumference of one tip plus its diameter. When the walls of the socket are collapsed so that the socket will assume the shape of an ellipse, a pair of tips may be readily inserted into the socket and when the walls have been released, the tips will be held in firm contact when the walls tend to resume the circular shape, although when a pair of tips is placed within the socket, the socket will be maintained in a distorted condition. As soon as the tips have been removed the sockets will again return to normal circular shape.

The mouths of the sockets may be flared as shown at 24 but such a construction is not required for the proper working of the device. The sockets are molded in long strips of resilient material, and the sockets may be connected by means of a web 25 as shown in Figure 3, or the sockets may be formed of a strip of material having substantially the same width throughout its length.

Referring more particularly to Figure 4, a modified form of connector is shown in 105 which the sockets 26 are formed at opposite

edges of a sheet of resilient material, such as rubber, and having partitions 27 separating the inner ends of the sockets 26.

- The sockets shown in the modified form 5 in Figure 4 are likewise formed of a single strip 28 of the material with the mouths of the socket opening in opposite directions along opposite edges of the strip, and it must be borne in mind that when the sockets are 10 made in the form shown in Figures 2, 3 or 4, they are all molded in single strips, and units of the sockets are cut from the strip as may be desired, the units comprising any number of sockets from two up.
- 15 Referring more particularly to Figure 5, a phone plug 29 is shown, which is adapted to be inserted in the jack and having a head 30 with passages 31 and 32 adapted to receive phone tips 33 and 34, respectively. The 20 central portion of a block 35 formed of resilient material is provided with an opening 36 adapted to snugly fit the head 30 of the plug 29, the tips 33 and 34 being inserted through the opening in the block at the rear 25 end of the same. Other phone tips which form part of the connection of four sets of phones are received within sockets 37, 38, 39 and 40, sockets 37 and 38 being at one end of the block 35, while the sockets 39 and 40 are 30 at the opposite end. The material of the block being resilient and compressible may be readily compressed upon its opposite faces in order to distort the circular sockets into an elliptical form, whereby the phone tips 35 may be readily inserted within the sockets. When the pressure has been released, the material will tend to assume its normal position, and thereby hold the phone tips in rigid contact with each other.
- 40 In all of the constructions, no metal parts are employed and since the material is made

of rubber or some other resilient composition the connectors may be placed upon the surfaces of furniture without any danger of marring the same.

45

I claim:

1. A connector for phone terminals comprising a plurality of sockets molded from a strip of resilient and non-conducting material, the sockets being connected by relatively thin webs of resilient material.
2. A connector for phone terminals comprising a strip of molded resilient material, said strip being provided with a plurality of sockets, said sockets having flared mouths to receive a pair of terminals.
3. A connector for phone terminals comprising a strip of resilient and non-conducting material, said strip having sockets moulded therein, the sockets being separated by walls of the material, the sockets being adapted to receive the phone terminals.
4. A connector for terminals of an electric circuit comprising a strip of elastic material having a plurality of sockets to receive pairs of the terminals, portions of the walls of the sockets being thinner than the remaining portions whereby said first mentioned portions of the walls may be distorted to receive the terminals and hold said terminals in close contacting relation.
5. A connector for terminals of an electric circuit comprising a plurality of sockets having walls formed of elastic material and means joining walls of the sockets together for reinforcing the walls along the points where joined together so that the free portions of the walls may be distorted to receive and hold said terminals in close contacting relation.

LEONARD FOOTE.
